UNITED STATES PATENT OFFICE.

HARRY P. MACDONALD, OF MONTCLAIR, NEW JERSEY, ASSIGNOR TO THE SNEAD & CO.
IRON WORKS, OF JERSEY CITY, NEW JERSEY, A CORPORATION OF NEW JERSEY.

ROLL RAMMING APPARATUS.

1,052,604.

Specification of Letters Patent.

Patented Feb. 11, 1913.

Application filed November 19, 1912. Serial No. 732,219.

To all whom it may concern:

Be it known that I, HARRY P. MACDONALD, a citizen of the United States, residing at Montclair, in the county of Essex and 5 State of New Jersey, have invented certain new and useful Improvements in Roll Ramming Apparatus, of which the following is a specification.

The invention relates to roll ramming apparatus, and it has for its primary objects the provision of improved means in roll ramming apparatus for striking off the sand, whereby a variable depth of the sand may be readily and simply obtained; and 10 the provision of means on the roll supporting track for elevating the strike-off mechanism at predetermined intervals, thereby leaving deeper portions of sand above the flask.

20 In general, my invention contemplates the provision of simple and effective means whereby the sand in any particular portion of the flask may be removed to a degree relatively harder than the remaining portions of the sand.

These, together with such other objects as may hereinafter appear or are incident to my invention, I attain by means of a construction illustrated in preferred form in 25 the accompanying drawings, wherein

Figure 1 is a longitudinal vertical view of a roll ramming apparatus and flask, showing the application of my improvements thereto, and Fig. 2 is a section on the line II-II of Fig. 1.

In forming molds for casting, having deep pockets or cores, such as exemplified for seal plates, it is particularly not convenient to ram the sand into such deep 35 portions of the mold, because, then the remaining parts of the mold, in order to insure compactness and strength of the sand at such portions, will ram the sand into such deep 40 portions of the mold harder than the remaining parts of the mold, in order to insure compactness and strength of the sand at such portions. This results in the danger of injury to such portions of the mold from 45 failing away of the casting when it is cast in the sand, or other causes, for a number of reasons, by scorching or casting the edges of the mold true and sharp. I accomplish this by leaving deeper portions of sand over the flask at such 50 points, and the roll in passing over such portions rams them to a degree harder than the balance of the flask.

Referring now to the drawings, it will be seen that I have shown a flask 7 carried on a 55 pattern support or table 8. Resting on the

top of the flask are two removable tracks 9 which are preferably angle sections and which are supported in any preferred manner. A ramming roll 10 is adapted to travel on the tracks 9 and is provided with grooves 11 with which the tracks engage. This construction is advantageous in that the tracks serve as an upset or retaining frame adapted to retain the uncompressed sand in position over the flask, and the engagement of the roll with the tracks prevents the latter from being spread apart by the pressure exerted by the roll on the sand during the ramming operation. It will also be obvious that the roll is thereby maintained in proper position. The roll is rotatably mounted in the frame 12 to which is secured an operating arm 13 which is actuated in any preferred manner.

In order to level off the sand in the flask 7 I have provided a strike-off frame 14 which is pivotally mounted on the axle of the roll and precedes the roll as the latter is operated. The strike-off frame extends across the front of the roll and adjacent either end is provided with brackets 15 in each of which is mounted a roller or wheel 16. These wheels engage the tracks and serve to support the strike-off frame in definite relation to the flask.

A number of pads 17, covering the strike-off frame, in order to leave deeper portions of sand over the flask, I provide a number of pads 17, which are detachably fastened to the tracks 9 by means of screws 18. The pads are preferably arranged in pairs, one for each track, and are located in corresponding positions, the number of the pads being determined by the character of the mold to be rammed. The location of the pads can be readily varied, as the tracks are provided with a plurality of screw-receiving holes 19, so spaced that the pads may be shifted to any desired point. The pads are so effectually fastened, and are so 100 spaced on the tracks that they are engaged by the wheels 16 when roll up the inclined surfaces of the pads as the roll is advanced, and elevate the lower portion of the strike-off frame, thereby leaving a deep portion of sand extending across the flask between the pads. The roll compacts all of the sand over the flask to a substantially uniform level, from which it naturally follows that the deep portions are packed to a greater 110

density and are therefore of a greater degree of hardness than the remaining portions of the sand. As previously pointed out, this construction is chiefly advantageous in forming molds for castings which have deep pockets or cores, and it insures the packing of sand for such portions to the proper degree, thereby improving the molds and reducing losses from breakage or 10 falling away to a minimum.

Another advantage of the construction is that it is especially useful to compact the sand more densely at points at which the casting is likely to strain, that is where the 15 pressure of the molten metal is greatest when the mold is being poured.

Having thus described my invention and illustrated its use, what I claim as new and desire to secure by Letters Patent, is the following.

1. A roll ramming apparatus comprising in combination, a flask, a ramming roll, a variable strike-off preceding the roll, and means whereby the strike-off is elevated to 25 leave a deeper portion of sand at a predetermined point in the flask.

2. A roll ramming apparatus comprising in combination, a flask, a ramming roll, a variable strike-off preceding the roll, a support for the roll adapted to support the roll 30 over the flask, and means on the support for elevating the strike-off to leave a deeper portion of sand at a predetermined point in the flask.

3. A roll ramming apparatus comprising in combination, a flask, a ramming roll, a variable strike-off preceding the roll, a support for the roll adapted to support the roll 35

over the flask, and cam means on the support for elevating the strike-off to leave a 40 deeper portion of sand at a predetermined point in the flask.

4. A roll ramming apparatus comprising in combination, a flask, a ramming roll provided with a variable strike-off, a support 45 for supporting the roll over the flask, means on the strike-off engaging the support, and cam means on the support adapted to elevate the strike-off and leave a deeper portion of the sand in the flask at a predeter- 50 mined point.

5. A roll ramming apparatus comprising in combination, a flask, a ramming roll provided with a variable strike-off, a pair of tracks for supporting the roll over the flask, 55 a pair of wheels on the strike-off adapted to ride on the tracks and a pair of cams mounted on the tracks in position to be engaged by the wheels, whereby the strike-off is elevated.

6. A roll ramming apparatus comprising in combination, a flask, a ramming roll, a support for the roll adapted to support it over the flask, a variable strike-off, camming means detachably carried on the support adapted to be engaged by the strike-off, and a plurality of cam positioning means on the support whereby the position of the camming means may be varied. 60

In testimony whereof I have hereunto 70 signed my name in the presence of the two subscribed witnesses.

HARRY P. MACDONALD.
